ABEL A. ADAMS, OF FELCHVILLE, ASSIGNOR TO RUSSELL W. PINNEY AND
FORREST L. PINNEY, OF BRIDGEWATER, VERMONT.

Letters Patent No. 82,269, dated September 22, 1868.

IMPROVEMENT IN HEAD-BLOCKS.

The Schedule referred to in these Letters Patent and making part of the same.

TO ALL PERSONS TO WHOM THESE PRESENTS MAY COME:

Be it known that I, ABEL A. ADAMS, of Felchville, of the county of Windsor, and State of Vermont, have invented a new and useful Improvement in Head-Blocks for Saw-Mills; and do hereby declare the same to be fully described in the following specification, and represented in the accompanying drawings, in which—

Figure 1 is a top view,

Figure 2 a front elevation,

Figure 3 a longitudinal section, and

Figure 4 a transverse section of my improved head-block.

In such drawings, A denotes the bed, having applied to it two head-blocks B C; they being so connected with it as to be capable of being moved rectilinearly therein, in a direction lengthwise of it.

Each of such head-blocks has a series of dogs, *a a*, extending through standards *b b*, arranged on it, and provided with set-screws *c c*, to hold the dogs in place after they may have been driven into a log.

Furthermore, there is a rack, *e*, to each of the standards, such being arranged in manner as represented, and for the purpose of enabling a person, by means of a lever resting at its foot against one of the teeth of a rack, to force back its dog, by pressure against the hook or head thereof.

The head-blocks are provided with clamp-screw bolts *e' e'*, which screw into nuts *f f*, arranged in a dovetailed groove, *g*, made in the bed; the purpose of such groove, bolts, and nuts being to enable a person to clamp the head-block in position on the bed. The saw-port or recess of the bed is shown at *h*.

In rear of such recess is a connection-bar, *i*, which rests on the bed in grooves made in the two head-blocks, and is fastened to the block C. A pin, *k*, going down through the head-block B, and into one of a series of holes made in the said bar, serves to so connect the auxiliary head-block C to the primary head-block B as to enable the former to be moved by the latter and its operative-mechanism. Another pin, *k'*, when inserted down through the head-block C, and into a hole in the bed A, serves to hold the head-block C stationary on the bed.

There is fixed to the bottom of the primary head-block a rack, *l*, which engages with a gear, *m*, fixed on a shaft, *n*, arranged in manner as represented.

There is another gear, *o*, on and fixed to such shaft.

Furthermore, a lever, *p*, so applied to the shaft as to be capable of turning freely thereon, carries not only a duplex rocker-frame, *q*, (provided with a working-arm, *r*) but also has a sector, *s*, extended from it, and aside of and over the gear *o*, in manner as represented. Through the said sector is a curved slot, *t*, through which, and a movable stop, *u*, a clamp-screw, *v*, is passed, and screws into a thumb-nut, *w*. The purpose of the screw and nut is to fix the stop in any desirable position on the periphery of the sector, on which is a scale of divisional marks and numbers.

Another stop-pawl, *x*, hinged to the bed, and formed and arranged, with respect to the gear *o* and sector *s*, in manner as shown in the drawings, has its free end bevelled, in order that, when pressed against such end, the sector shall force up the stop-pawl, in order that the sector may pass underneath it, and the other stop-pawl be brought up in contact with it.

An abutment or stop, *y*, extended from the bed, serves to limit the descent of the lever *p*, which, when in its lowest position, rests on such abutment. A spring, *z*, extends from the working-arm, and underneath and against a stud, *a'*, projecting from the lever *p*. A graduating-pawl, *b'*, (applied to the front of the bed,) when turned against the gear *o*, serves to prevent it from being revolved in one direction.

The purpose of the sector *s*, its adjustable stop *u*, the hinged stop-pawl *x*, and the abutment *y*, is to regulate the amount of vibration of the lever *p*, in order to effect equal movements of the head-block, the length of each of such movements depending on the distance of the stop *u* from the upper end of the sector.

The auxiliary head-block enables sawing to be effected on one log while the other head-block is being moved back to place for reception of another log.

By laying hold of the working-lever, and raising it, while, at the same time, we raise the lever *p*, we cause the duplex-pawl to actuate the gear *o*, in a manner to effect the backward movement of the main head-block.

By means of the lever *p* and its working-pawl, we can operate the gear *o* in either direction, the sector *s*, the adjustable stop *u*, the hinged stop-pawl *x*, and the stationary abutment *y* serving to regulate the distance of each vibration of the lever, in order to effect equal movements of the head-block or blocks.

What I claim as my invention is as follows:

I claim the combination of the sector *s*, its adjustable stop *u*, and hinged stop-pawl *x*, with the gear *o*, its operating-lever *p*, working-pawl *q*, and abutment *y*, the same being applied to the bed, and to the shaft of the rack-pinion of the main head-block, substantially in manner and for the purpose or objects as set forth.

ABEL A. ADAMS.
